UNITED STATES PATENT OFFICE.

OSCAR B. BACH, OF NEW YORK, N. Y.

DESIGN FOR AN END TABLE.

Application filed April 5, 1927. Serial No. 21,461. Term of patent 3½ years.

To all whom it may concern:

Be it known that I, OSCAR B. BACH, a citizen of the United States, residing at New York city, in the county of New York and State of New York, have invented a new, original, and ornamental Design for an End Table, of which the following is a specification, reference being had to the accompanying drawing, forming part thereof, in which—

Fig. 1 is a top plan view, showing my new design and Fig. 2 is a perspective view of an end table showing my new design.

I claim the ornamental design for an end table, as shown.

OSCAR B. BACH.
